UNITED STATES PATENT OFFICE.

THEODORE JOHN SIMONS, OF HASKINS, IOWA.

SLIDING HAY-DOOR.

1,223,528.

Specification of Letters Patent.

Patented Apr. 24, 1917.

Application filed August 11, 1915. Serial No. 45,004.

To all whom it may concern:

Be it known that I, THEODORE JOHN SIMONS, a citizen of the United States, residing at Haskins, in the county of Washington and State of Iowa, have invented certain new and useful Improvements in Sliding Hay-Doors, of which the following is a specification.

My invention relates to an improvement in sliding hay-doors, the object being to provide a door which operates on an inclined track more or less by gravity, and is counterweighted to facilitate moving back and forth.

15 In the accompanying drawings:

Figure 1 is a view in elevation showing the doors partly open, and operating mechanism partly exposed;

Fig. 2 is a similar view on a large scale partly in section;

Fig. 3 is a fragmentary view of one of the guide hangers;

Fig. 4 is a plan view of one end of the guide hanger;

25 Fig. 5 is a detail of one form of pulley; and

Fig. 6 is a detail of another form of pulley employed.

A, A, represent the two doors for closing the opening 1 in the barn-gable. Inclined tracks 2, 2, are secured outside the rafters 3, 3, to be out of the way.

Two guide-hangers, preferably, are secured to the upper inclined edge of each door, as shown in Fig. 1. These guide-hangers comprise a frame 4, as shown in Fig. 3, and two grooved rollers 5, 5, and the shank 6 at the center is bolted to the door as at 7, 7. A swivel 8 at one end of the frame 4 has the cable 9 attached to it, and this cable passes over the upper pulley 10, located approximately at the point of the gable, and the cable thence passes downward inside the rafter, and thence over the pulley 11, and has a weight 12 on its lower end.

A guard 13, preferably made of gas pipe or other tubular material, is secured at its ends on the two supporting-irons 14, 14, secured to the barn, and between the surface

of which and the guard 13 the doors are slid, 50 the irons 14, 14, serving as stops when the doors are slid open.

In this way I have provided a very simple means for opening and closing a door-way, located at the gable of a barn, utilizing the 55 inclination of the gable rafters to form supports for the inclined track on which the guide-hangers travel, so that in opening the door all the operator has to do is to push them aside, and, while opening, the doors 60 descend more or less, according to the slope of the roof, utilizing gravity to assist them in this movement, and their weight being counterbalanced it is equally convenient to slide the doors together up the inclination 65 of the track when they are to be closed.

A door of this kind is easily applied to any barn having a gable-roof, or in fact any sloping roof, as it is evident that a single door instead of two might be used if the 70 roof had but one slope instead of a double slope, and it is equally evident that the door could be operated, as shown, from the floor on which the door or doors are located, or from any floor below, by simply extending 75 the cables 9 which control the door.

I claim:

The combination of an inclined track, a door, a guide hanger comprising a frame and grooved rollers mounted diagonally upon 80 said track and provided with a vertically disposed shank secured to the door, four pulleys, one located at each end of the track, the third pulley adjacent to the lower end of the track, the fourth pulley at some point 85 below said last mentioned pulley, a cable secured at one end to the guide hanger and rove over the four pulleys, and a weight to which one end of the cable is secured and with which another portion of the cable is 90 connected.

In testimony whereof I affix my signature, in the presence of two witnesses.

THEODORE JOHN SIMONS.

Witnesses:

SCHUYLER W. LIVINGSTON,
T. B. SIMONS.
